TRANSFORMER RELAY

Albert L. Judson, Minneapolis, Minn., assignor to
Minneapolis-Honeywell Regulator Company,
Minneapolis, Minn., a corporation of Delaware

Original application December 7, 1932, Serial No.
646,080. Divided and this application March
11, 1937, Serial No. 130,275

2 Claims. (Cl. 200—91)

This application is a division of my prior application, Serial No. 646,080, filed Dec. 7, 1932, for Burner control apparatus, which became Patent No. 2,075,289 on March 30, 1937. The present application is directed to the new and novel transformer relay shown and described in the prior application.

An object of the present invention is to provide a transformer relay of simple compact form which is particularly free from vibration arising from the alternating current power supply.

The invention resides in the various constructional details by which the above object is accomplished.

For a more detailed understanding of the invention, reference is made to the accompanying drawing in which:

Figure 1 is a front elevational view of the improved transformer relay with the armature thereof in its normal deenergized position;

Figure 2 is a front elevational view of the relay with the switch removed to more clearly show other elements of the relay and with the relay armature shown in its energized position; and

Figure 3 is a perspective view of the relay armature and the switch positioned thereby.

Referring to Figure 1 of the drawing, the transformer relay of the present invention broadly comprises a primary winding 11 and a secondary winding 12, the two windings being located upon a core 13 in the form of a rectangular frame. Pivoted secured to the frame is an armature generally indicated by the reference numeral 15 and this armature carries a mercury switch 16. The winding 11 is maintained permanently energized and the circuit of secondary winding is opened or closed, depending upon the desired position of armature 15. The armature 15 is shown in Figure 1 in the position assumed when the circuit of secondary 12 is open and is shown in Figure 2 in the position occupied when the circuit of secondary 12 is closed. Legends have been applied to the primary and secondary windings to enable them to be more readily distinguished from an inspection of the drawing.

The core 13, as shown in the drawing, comprises a plurality of laminated bars secured together in rectangular formation. The four legs of the rectangular core frame are designated by the reference numerals 18, 19, 20, and 21, the legs 18 and 20 being relatively long as compared to the legs 19 and 21. The primary coil 11 is disposed around the longer leg 20 and the secondary coil 12 is disposed around the shorter leg 21 and 55 at right angles to the primary coil 11. It will

be noted that by reason of the way in which transformer windings 11 and 12 are disposed the space between the legs of the transformer frame is almost entirely filled. The various laminations of the transformer are held together by rivets 5 25. The transformer frame 13 can if desired be secured to any suitable base (not shown) by screws 24 extending therethrough.

The armature 15 is formed of a pair of generally U-shaped members 26 and 27 of magnetic material. The bases of these two members are held in close engagement with each other by any suitable fastening means. The upper ends of the members 26 and 27 are formed so as to provide one element of a pivotal connection. It 10 will be noted that the member 27 has its upper end formed in an arcuate fashion and the end of member 26 extends adjacent to this arcuate portion. The armature is pivotally held in position within an extension of the leg 20 by means of a 15 pivot pin 30.

The lower ends of the U-shaped members 26 and 27 are spread slightly apart so as to permit shading rings 32 to be placed over the lower end of member 27. By the use of the two members 25 26 and 27, it is unnecessary to slot the lower end of the armature to accommodate this shading means, as is usually necessary.

Secured to the armature assembly 15 is an L-shaped bracket 34 and an arm 35. The bracket 30 34 and the arm 35 are held in position by a screw 36. The mercury switch 16 is secured to the arm 35. This switch, as is conventional, comprises a sealed envelope enclosing a pair of electrodes 39 and 40. Also located within the envelope is a 35 pool 38 of mercury. The mercury 38, when the switch 16 is tilted in the position shown, is disposed away from the electrodes. Upon the switch 16 being tilted to horizontal position however, the mercury is moved into bridging engagement with 40 the electrodes, as is conventional. The mercury 38 within the switch 16 is relatively heavy due to the high density of mercury. The switch 16, it will be noted, is disposed on the right-hand side of the pivot 30 so that the mercury 38 is 45 effective to bias the armature 15 to its open position, as shown in Figure 1. In order to insure, however, that the armature will always move to its deenergized position, it is necessary to further provide a weight 42 as a biasing means. The 50 weight 42 is secured to the left-hand end of arm 35 by means of a screw 43. The relay arm 15 is thus biased to its deenergized position by the combined action of weight 42 and switch 16.

The L-shaped bracket 34 is provided with a 55

horizontal arm 45, the left-hand end of which abuts against the right-hand end of leg 20 of the core. The bracket 34 thus serves to limit the movement of the armature when tilted counter-clockwise by the biasing action of weight 42 and switch 16.

Operation

As previously noted, the primary winding 11 is normally constantly energized. The circuit of secondary winding 12 is normally open and the parts are in the relative positions shown in Figure 1. As long as the secondary winding 12 is thus open, the flux generated in winding 11 flows through the leg 21 since this is the path of least resistance for the flux. When it is desired to move the switch 16 to the closed position, the circuit of secondary 12 is closed, either short-circuiting or substantially short-circuiting this winding. When this happens, the reluctance of leg 21 is enormously increased so that the flux tends to be forced through the armature 15 and the air gap between the lower end of the armature. The armature 15 is thereupon rotated in a clockwise direction against the combined action of weight 42 and switch 16. This results in clockwise rotation of switch 16 to its closed position in which the mercury 38 bridges the electrodes 39 and 40. The armature is held in the switch closed position with a negligible amount of hum due to the shading rings 32.

By designing secondary 12 so as to produce a relatively low voltage, it is possible to use low voltage switches in the control of the circuit of the secondary winding 12. The secondary winding 12 may also, if desired, be used to energize other devices such as an electrical heating resistance. The relay transformer thus combines the functions of a step-down transformer and a relay. By reason of the extremely compact disposition of the windings by the manner in which the armature closely encircles the secondary winding, the unit occupies less space than the ordinary transformer.

Without further elaboration, the foregoing will 45 so fully explain the gist of my invention that others may, by applying current knowledge, readily adapt the same for use under varying conditions of service, without eliminating certain features which may properly be said to constitute the 50 essential items of novelty involved, which items are intended to be defined and secured to me by the following claims.

I claim as my invention:

1. A transformer type electromagnetic actuator comprising; a core member forming a rectangular frame composed of two cross legs and two side legs; a winding upon one of said cross legs and a winding upon one of said side legs; an armature pivotally secured to said frame, said armature comprising a pair of U-shaped members fastened together adjacent their mid point and of a configuration to extend closely around one of said core windings, said U-shaped members being shaped at one end to form an element of a hinge connection with said frame while being spread apart at the other end of said armature and disposed so as to be movable into engagement with said frame, a shading ring secured over one of 10 said U-shaped members at the end at which they are spread apart, means for biasing the armature to normally maintain an air gap between the end carrying the shading ring and said rectangular frame, the said armature being actuated to form 20 a magnetic shunt around a portion of the core when both of said windings are energized.

2. In a transformer relay; a core member having two cross legs and two side legs, said legs being disposed perpendicularly to one another to 25 form a rectangular frame; a low voltage control secondary winding upon one of said cross legs; a high voltage primary winding upon one of said side legs; an armature pivotally secured to said frame, said armature comprising a pair of U- 30 shaped members fastened together adjacent their mid point and of a configuration to closely extend around said secondary windings, said U-shaped members being shaped at one end to form an element of a hinge connection with said frame 35 and being spread apart at the other end of the armature and disposed so as to be movable into engagement with said frame so that said armature forms a magnetic shunt around that portion of the core on which said secondary winding is 40 located when actuated under control of said secondary winding; a shading ring secured over one of said armature members at the end at which said members are spread apart; a mercury switch secured to said armature and operated thereby; and means including said mercury switch and a counterweight secured at a point intermediate the pivot and movable end of said armature for biasing said armature so that the end carrying the shading ring is normally spaced from said rectangular frame to provide an air gap in the shunt path including said armature.

ALBERT L. JUDSON.
